[57] CLAIM

The ornamental design for a computer cursor controller, as shown and described.

DESCRIPTION

FIG. 1 is a perspective view of a first embodiment of a computer cursor controller showing our new design, the broken line illustration of the base portion is for illustrative purposes only;

FIG. 2 is a front view thereof;

FIG. 3 is a top view thereof;

FIG. 4 is a right side view thereof, the left side view being a mirror image thereof;

FIG. 5 is a back view thereof;

FIG. 6 is a perspective view of a second embodiment of a computer cursor controller showing our new design;

FIG. 7 is a front view thereof;

FIG. 8 is a top view thereof;

FIG. 9 is a right side view thereof, the left side view being a mirror image thereof; and,

FIG. 10 is a back view thereof.
